SHIRT

Elma G. Williams, Takoma Park, Md. (P.O. Box 129,
Letterman General Hospital, San Francisco, Calif.
94129)

Filed July 9, 1969, Ser. No. 18,133

Term of patent 7 years

Int. Cl. D2—01
U.S. Cl. D2—217

FIG.1.

FIG. 4.

FIG. 2.

FIG. 3.

FIGURE 1 is a front elevational view of a shirt, showing my new design.

FIGURE 2 is a rear elevational view thereof.

FIGURE 3 is an enlarged fragmentary longitudinal sectional view, taken substantially along a plane as indicated by the line 3—3 of FIGURE 1.

FIGURE 4 is an enlarged fragmentary longitudinal sectional view, taken substantially along a plane as indicated by the line 4—4 of FIGURE 1.

I claim:

The ornamental design for a shirt, as shown.
